(57) **CLAIM**

The ornamental design for commemorative sports award trophy, as shown and described.

DESCRIPTION

FIG. 1 is a perspective view of the commemorative sports award trophy showing the new design comprising a commemorative basketball and a stand resembling the top of a basketball hoop. The ornamental colors may be applied to the top and bottom sections of the commemorative basketball. The ornamental colors that are so applied may be different colors.

FIG. 2 is a front view of the commemorative sports award trophy.

FIG. 3 is a rear view of the commemorative sports award trophy.

FIG. 4 is a top view of the commemorative sports award trophy.

FIG. 5 is a left side view of the commemorative sports award trophy; and,

FIG. 6 is a right side view of the commemorative sports award trophy.

The bottom of the claimed design is flat and devoid of surface ornamentation. A bottom view of the claimed design is therefore not included. In all figures, the broken line showing of a commemorative sports award trophy is included for the purpose of illustrating environmental structure and forms no part of the claimed design.
